ABSTRACT

A safety valve well tool movable to a subsurface location through a bore of a production tubing for securing therewith in response to a predetermined fluid pressure for thereafter controlling undesired upwardly flow through the bore of the production tubing with a rotatable ball valve operating in response to a control fluid pressure communicated to the well tool through an annular passageway.

IN-TUBING SAFETY VALVE WELL TOOL

CROSS-REFERENCE TO RELATED APPLICATIONS

This is a continuation of application Ser. No. 291,561 filed Sept. 25, 1974 now abandoned.

BACKGROUND OF THE INVENTION

This invention relates to the field of subsurface safety valves for use in wells.

While surface controlled safety valve well tools movable through a bore of a production tubing to a subsurface operating location are known, these well tools have previously required that the numerous costly and extremely hazardous installation and retrieval operations be performed downhole under well pressure. Other surface controlled safety valve well tools having an annular fluid pressure control passageway means, such as disclosed in U.S. Pat. Nos. 3,065,793, 3,065,794, 3,094,170, 3,332,497 and 3,497,004, required pulling the production tubing to retrieve the valve or holding a control fluid pressure with the casing either of which requirement increased the cost of the produced well fluids.

SUMMARY OF THE INVENTION

A new and improved well tool movable through a bore of a production tubing including a housing mounting a rotatable ball bore closure means for controlling flow through the bore of the production tubing and which is releasably secured therein by a predetermined fluid pressure. The housing is connected with a second production tubing and communicating desired flow to the earth surface which is concentrically positioned in the bore of the production tubing to form an annular flow passage therebetween for supplying control fluid pressure to the housing for operating the ball.

An object of the present invention is to provide a new and improved safety valve well tool.

A further object of the present invention is to provide a new and improved in-tubing safety valve.

Yet another object of the present invention is to provide a new and improved surface controlled subsurface safety valve.

BRIEF DESCRIPTION OF THE DRAWINGS

FIG. 1 is a side view, partially in section, illustrating the well tool of the present invention secured at a subsurface location in a bore of a production tubing;

FIGS. 2A, 2B, 2C and 2D are side views, partially in section, illustrating the well tool prepared for running in the well;

FIGS. 3A and 3B are side views, partially in section, illustrating the well tool secured with the production tubing;

FIGS. 4A and 4B are side views, partially in section, illustrating the valve operated open; and

FIGS. 5A, 5B, 5C and 5D are views similar to FIGS. 4A, 4B, 4C and 4D, respectively, illustrating the well tool during retrieval from the well.

DESCRIPTION OF THE PREFERRED EMBODIMENT

The well tool of the present invention, generally designated T, is operably positioned in a bore O of a production tubing P at a subsurface or downhole location of a well W for controlling undesired upwardly flow of

well fluids through the bore O of the production tubing P in response to a controlled fluid pressure communicated to the well tool T. An annular seal between the production tubing P and a well casing C effected by a well packer (not illustrated) directs upwardly flow from the well W through the bore O of the production tubing P to the well tool T. Desired upwardly flow from the well tool T is communicated through the bore of a second or inner production tubing or conduit Q positioned in the bore O of the production tubing P to a christmas tree X located at the earth surface or ground G. The christmas tree X provides a manifold for flowing the hydrocarbons and well fluids from the well W through the conduit A while communicating a source of controlled fluid pressure (not illustrated) through a conduit F with the well tool T for effecting operation thereof to control flow of fluid through the bore O of the production tubing P. The production tubing P is normally positioned in the well casing C, but the casing C is not required as the well tool T is equally adapted for use in wells W without the casing C.

The well tool T includes a housing H mounting thereon a securing means L and a seal means R which is movable through the bore O of the production tubing

25 P to the desired subsurface location where the securing means L operates to mount the housing H with the production tubing P while the seal means R effects an annular seal between the housing H and the production tubing P. The well tool T further includes a bore closure means B movably mounted with the housing H and an actuator means D for effecting movement of the bore closure means B to an open position for enabling flow of fluids through the bore O of the production tubing P and to and from a closed position for substantially 30 blocking flow of fluid through the bore O of the production tubing P.

As illustrated in FIG. 2A, the housing H includes an upper or fixed sleeve 10 and an intermediate or movable portion sleeve 11 secured together by threaded engagement at 10a with an O-ring 12 blocking leakage of fluid between the sleeves 10 and 11. The fixed sleeve 10 includes a threaded box connection (not illustrated) to secure the well tool T with the second production tubing Q for communicating flow of fluid through a 40 longitudinally extending bore or flow passage M of the housing H through the second production tubing Q to the christmas tree X. The flow passage M is defined through the sleeve 10 by an inner surface 10b forming an upwardly facing annular shoulder 10c for receiving thereon a landing shoulder (not illustrated) of a plug means E (FIG. 3A), for supporting and properly positioning the plug means E in the flow passage M as is well known in the art.

45 The sleeve 11 extends downwardly from an upper annular shoulder 11a, adjacent threads 10a, to a lower annular shoulder 11b (FIG. 2C) with an inner surface 11c defining a portion of the longitudinally extending housing flow passage M while an outer surface 11d serves as a movement guide for the securing means L concentrically mounted thereon.

The housing H further includes a lower sleeve 13, operably connected with the fixed sleeve 10 and which extends upwardly from a downwardly facing lower annular shoulder 13a (FIG. 2B) to an upwardly facing annular shoulder 13b (FIG. 2C) above the seal means R with an inner surface 13c defining a bore or opening 13d through the sleeve 13 for concentrically mounting

the sleeve 13 in telescoping relationship with the sleeve 11 and for forming a portion of the flow passage M for communicating the flow of fluid through the housing H.

The bore closure means B is movably disposed in the bore 13d and includes a rotatable ball member 20 and a pair of inwardly extending pivot pins 21 secured to the sleeve 13 at eccentric positions by threads 21a for mounting the ball 20 with the sleeve 13. The ball 20 is provided with a flow opening 20a therethrough and a pair of parallel, flat circular surfaces 20b having a radially extending recess or groove 20c formed in each of the flats 20b for receiving the pivot pin 21 therein. Longitudinal movement of the ball 20 relative to the pivot pins 21 will impart relative rotation to the ball 20 to and from an open or lower position (FIG. 4B) aligning the opening 20a with the housing flow passage M for enabling flow of fluid through the well tool T and to and from a closed or upper position (FIG. 2D) for substantially blocking flow of fluid through the passage M and the bore O of the production tubing T. Reference is made to my co-pending application entitled "PRESSURE OPERATED SAFETY VALVE WITH LOCK MEANS", Ser. No. 72,034, filed Sept. 14, 1970, abandoned after filing of continuation application Ser. No. 256,194 on May 23, 1974, for a more detailed description and illustrations of the relationship of the pivot pins 21 and the ball 20 in rotating to and from the open and closed positions when there is relative movement therebetween.

The actuator means D includes a pair of movable sleeve operators 30 and 31 positioned in the bore 13d above and below the ball 20, respectively, for effecting the required longitudinal movement of the ball 20 to rotate the ball 20 open and closed. The sleeves 30 and 31 are longitudinally movable to and from a first or lower position (FIG. 4A and 4B) for effecting opening rotation of the ball 20 and to and from a second or upper position (FIGS. 2C and 2D) for rotating the ball 20 closed. The lower sleeve 31 includes an outer surface 31a having an outwardly projecting annular collar 31b formed thereon to provide a downwardly facing annular shoulder surface 31c and an upwardly facing annular shoulder surface 31d which engage spaced annular shoulders 13e and 13f, respectively, to provide movement limit stops for the sleeve 31. The sleeve 31 is normally urged to move to the upper position by a spring means 32 concentrically mounted about the sleeve 31 between the shoulder 31c and an annular shoulder 13g formed on the sleeve 13 and which is imparted to the ball 20 by an upper arcuate annular surface 31e engaging an outer spherical sealing surface 20d of the ball 20.

The upper sleeve 30 includes a downwardly facing arcuate annular shoulder 30a which engages the spherical surface 20d for moving the ball 20 downwardly to effect opening rotation of the ball 20 and to effect an annular seal between the ball 20 and the sleeve 30 to block upwardly flow of fluid in the passage M when the ball 20 is rotated closed. The sleeve 30 further includes an outer surface 30b mounting the sealing element 33 (FIG. 2C) thereon to effect a sliding seal with the lower housing sleeve 13 to block leakage of fluid therebetween and an outwardly projecting annular collar 30c forming an upwardly facing annular shoulder surface 30d and a downwardly facing annular shoulder surface 30e. The sleeve 30 is normally urged to move to the upper position by a biasing means or spring 34 concen-

trically mounted about the sleeve 30 between an upwardly facing shoulder 13h of the sleeve 13 and the shoulder 30e which moves the shoulder 30d into engagement with the shoulder 11b to provide an upper movement limit stop for the sleeve 30. Mounted on the collar 30c is an O-ring 36 for effecting a sliding annular seal with the surface 13c of the sleeve 13 to block leakage of fluid therebetween with the seal 33 blocking communication of fluid pressure in the bore 13d below the ball 20 to the shoulder surface 30e. The intermediate sleeve 11 mounts an O-ring 14 in a recess formed on the surface 11c adjacent the shoulder 11b to effect a sliding seal with the surface 30b of the sleeve 30 above the collar 30c to provide a pressure responsive effective surface area on the sleeve 30, designated 30d, between the seals effected by the O-rings 14 and 36 for urging the sleeve 30 to move downwardly to rotate the ball 20 open.

As illustrated in FIG. 2A, the means for releasably securing the housing with the production tubing is operable in response to a predetermined fluid pressure and includes a movable lower or first wedge 40, an upper or second wedge 41, and a plurality of three slips 42 engaging the wedges 41 and 42 for effecting operational movement of the slips 42. The slips 42 are movable to and from a retracted or free position (FIGS. 2A and 5A) enabling the housing to move through the bore O of the production tubing P and to and from an expanded or locked position (FIG. 3A) for engaging and frictionally gripping the production tubing P to block relative movement between the slips 42 and the production tubing P. The slips 42 are positioned in a corresponding plurality of three windows or apertures 41a which are equally circumferentially spaced about the sleeve-like upper wedge 41 with an upper tapered inner edge of the slips 42a engaging a tapered upper surface 41b of the windows 41a for moving the slips 42 radially as they move longitudinally along the surface 41b. The upper wedge 41 is concentrically mounted with the sleeve 10 by an upwardly facing annular shoulder 10d engaging a downwardly facing annular shoulder surface 41c which enables relative circumferential rotational movement between the upper wedge 41 and the tubular member 10 when the tubular member 10 is rotated to partially disengage the threads 10a while blocking relative longitudinal movement therebetween during such rotation. The wedge 41 is concentrically mounted with the sleeve 11 with an inwardly projecting bolt or threaded pin 41d secured with the upper wedge 41 extending into a longitudinally extending slot or groove 11e formed in the outer surface 11d of the sleeve 11 and which blocks relative circumferential rotation between the tubular member 11 and the wedge 41 while enabling limited longitudinal movement therebetween when the sleeve 10 is rotated to partially disengage the threaded engagement at 10a.

The lower wedge 40 includes a tapered upwardly facing annular shoulder surface 40a engaging a lower tapered inner surface 42b of the slips 42 for wedging or forcing the slips 42 radially outwardly as the lower wedge 40 moves longitudinally from a first or lower position (FIG. 2A) to a second or upper position (FIG. 3A) toward the upper wedge 41. As illustrated in FIG. 2B, the lower wedge 40 is preferably in the form of a sleeve which extends downwardly from the upper annular shoulder 40a to a downwardly facing annular shoulder 40b with a longitudinal movement guiding

inner surface 40c thereof forming a downwardly facing pressure responsive annular shoulder surface 40d for urging upward movement of the wedge 40 and which is located adjacent an opening or port 11f formed through the sleeve 11. The wedge 40 is concentrically mounted with the sleeve 11 and carries an O-ring 43 thereon to effect a sliding annular seal with the sleeve 11 to block leakage of fluid therebetween.

Mounted below the shoulder 40d in the concentric annular space between the wedge 40 and the sleeve 11, is a piston ring 44 and a detent latch assembly 45 for maintaining the wedge 40 in the upper position to hold the slips 42 in the locked position. The piston 44 is slidably sealed to the sleeve 11 and the wedge 40 by O-rings 44a and 44b, respectively, to provide an upwardly facing pressure responsive annular surface 44c adjacent the port 11f for urging the piston 44 to move downwardly in response to the predetermined fluid pressure communicated through the port 11f and urging thereon.

The detent assembly 45 includes a ring member 46 having a plurality of four circumferentially equally spaced windows or apertures 46a formed therein for mounting therein a corresponding plurality of movable detents 47 having a saw-tooth surface 47a biased towards engagement with the wedge 40 by a spring means 48 mounted with the ring 46. The saw-tooth surface 47a of the detent 47 is shaped to enable upward movement of the wedge 40 relative to the detent 47 while downward movement of the wedge 40 along the surface 47a moves the detents 47 to engage and move longitudinally along a tapered lower surface 46b of the windows 46a to wedge the detent 47 to move radially outwardly to block any downward movement of the wedge 40 relative to the detent 47. The detent ring 46 is initially blocked from downward movement by a snap-ring 49 mounted below the ring 46 and which is easily moved downwardly along with the ring 46 when the predetermined fluid pressure is applied to the piston 44 for moving the ring 46 downwardly by engagement of adjacent annular shoulders 46c and 44d.

The lower wedge 40 is illustrated, in an incorrect sectional view in FIG. 2A, connected with the upper wedge 41 by a threaded pin or bolt 40e secured with the lower wedge 40 and which extends outwardly within a longitudinal window slot 41e formed through the wedge 41 to enable limited relative longitudinal movement therebetween while blocking relative circumferential rotational movement. Concentrically mounted with the tubular member 11 below the wedge 40, is a floating sleeve 50 (FIG. 2B) having a threaded connector pin or bolt 50a secured thereto which extends outwardly into a longitudinal extending window slot 40f formed through the wedge 40 for connecting the wedge 40 and the floating sleeve 50 to enable limited relative longitudinal movement therebetween while blocking circumferential rotational movement therebetween similar to the connection between the wedges 40 and 41 by the pin 40e and which is also illustrated in perspective.

The floating sleeve 50 extends downwardly from an upwardly facing annular shoulder 50b adjacent the snap-ring 49 (FIG. 2B) to a downwardly facing annular shoulder 50c (FIG. 2C) adjacent the seal means R and having a longitudinal slot 50d formed therethrough adjacent the shoulder 50c for receiving therein an outwardly projecting threaded bolt or pin member 13i se-

cured to the sleeve 13 for connecting the lower sleeve 13 with the floating sleeve 50 for enabling limited relative longitudinal movement while blocking relative circumferential rotational movement therebetween.

Concentrically mounted with the sleeve 13 below the annular shoulder 50c of the floating sleeve 50 is the sealing means R including a replaceable resiliently deformable sealing element 60 which is forced or wedged to expand radially outwardly into annular sealing engagement with the production tubing P (FIG. 3B) by longitudinal upward or contracted movement of the sleeve 13 toward the annular shoulder 50c of the sleeve 50 while longitudinal downward movement of the sleeve 13 from the sleeve 50 (FIGS. 2C and 5C) stretches the sealing element 60 to contract sufficiently radially inwardly to enable the housing H to move through the bore O of the production tubing P.

In the use and operation of the present invention, the well tool T is assembled in the condition illustrated in the FIGS. 2A, 2B, 2C, and 2D, and transported to the site of the well W. The well tool T is then connected with the inner production tubing Q using the threaded box connections (not illustrated) as is well known in the art and lowered down the bore O of the production tubing P to the desired subsurface location for setting the well tool T by the addition of tubing joints to the inner production tubing Q.

When the well tool T is at a desired subsurface location the plug means E is lowered down the bore of the inner production tubing Q where it is received in the flow passage M of the housing H (FIG. 3A) and positioned and secured therein by engagement with the landing shoulder 10c as is old and well known in the art. The plug means E includes a downwardly extending extension 71 from the landing shoulder (not illustrated) to an enlarged head 71a mounting a plurality of replaceable annular packing or seal rings 71b thereon to block communication of the flow passage M above and below the seals so effected by the seal rings 71b. The extension 71 of the plug means E is suitably dimensioned to locate the seal rings 71b below the flow port 11f when the plug means E is properly positioned in the housing H to enable a pump or other pressure generating means (not illustrated) connected to the conduit A of the christmas tree X to increase the pressure in the passage M above the rings 71b. This fluid pressure is communicated in this predetermined manner through the port 11f to urge on the pressure responsive shoulder 40d for urging the lower wedge 40 to move upwardly while urging on the shoulder 44c of the piston 44 for urging the piston ring 44 and the detent assembly 45 to move downwardly.

As illustrated in FIG. 3A, the upward movement of the wedge 40 forces the plurality of slips 42 outwardly to engage the production tubing P with a serrated outer surface 42c for increasing the frictional engagement therebetween to enable the securing of the housing H with the production tubing P at any desired subsurface location. While the wedge 40 is moving upward relative to the saw-tooth detent 47, the piston 44 is urging the ring 46 to move downwardly and bringing the split-ring 49 into full engagement with the annular shoulder 50b of the floating sleeve 50. Such movement is illustrated in greater detail by comparing the relative position of the pin 50a in the slot 40f in FIGS. 2B and 3B. Thereafter, the saw-tooth edge 47a of the detent 47 will block downward movement of the lower wedge 40 from the

upper position and maintain the slips 42 in the radially expanded locked position. When the pressure in the flow passage M above the seals 71b is reduced, the plug means E may then be retrieved back to the surface G and removed from the well W by any suitable tool as is well known in the art.

When the pressure in the passage M above the ball 20 is reduced below the pressure in the bore O of the production tubing P below the closed ball 20, such as by venting from the conduit A, a pressure differential will be established across the ball 20 for urging upwardly movement thereof. This urging will move both the ball 20 and the sleeve 13 upwardly relative to the floating sleeve 50 which is blocked from moving upwardly relative to the wedge 40 by engagement of the shoulder 50b with the ring 49.

The relative upward movement of the sleeve 13 to the floating sleeve 50 will deform the sealing element 60 sufficiently to effect an annular seal about the tubular member 13 with the production tubing P to block leakage of fluid therebetween. This relative motion is also illustrated by comparing the position of the threaded pin 13i in the slot 50d in FIGS. 2C and 3B. The unbalanced upwardly urging of the well pressure on the sleeve 13 will thereafter maintain the sleeve 13 in this position relative to the floating sleeve 50.

The establishment of an annular seal by the sealing element 60 thus defines an annular passageway for communicating control fluid pressure communicated into the bore of the production tubing O at the Christmas tree X through the conduit F to a location adjacent the well tool T and above the annular seal 60.

As illustrated in FIG. 4A, this annular control fluid pressure is communicated through the slot 50d of the floating sleeve immediately above the sealing element 60 to a longitudinally extending recess 11g formed in the outer surface 11d of the sleeve 11 adjacent the sealing element 60 for communicating the fluid pressure above the annular shoulder 13d of the sleeve 13 to an annular chamber formed between the sleeves 11 and 13 above the pressure responsive annular shoulder surface 30d of the operator 30. The control fluid pressure communicated to the well W through the conduit F will thus be communicated to the shoulder 30d for urging the operator 30 to overcome the upwardly urging of the springs 32 and 34 to move the operator sleeves 30 and 31 and the ball 20 to the lower positions for effecting opening rotation of the ball 20 and enabling flow of fluids through the flow passage M.

When it is desired to block flow of fluid from the well W the control fluid pressure in the conduit F is reduced, enabling the springs 32 and 34 to move the operator sleeves 31 and 30, respectively, to the upper position for rotating the ball 20 closed and maintaining the ball 20 in that position until the control fluid pressure is again introduced to the conduit F for effecting opening rotation of the ball 20.

When it is desired to retrieve the well tool T from the well W back to the surface G, it is only necessary to impart right-hand rotation of the inner production tubing Q at the Christmas tree X to effect partial disengagement of the threaded connection 10a between the tubular member 10 and the tubular member 11. As illustrated in FIG. 5a, this effects a relative upward movement of the upper wedge 41 and the tubular member 10 from the lower wedge 40 to space the wedges 40 and 41 sufficiently for enabling the slips 42 to move in-

wardly to the free position as illustrated. With the slips 42 in the free position, the inner production Q is elevated to bring the threaded member 50a of the floating sleeve 50 into engagement with the lower edge of the slot 40f to move the floating sleeve 50 upwardly relative to the lower sleeve 13 and enabling the sealing element 60 to contract inwardly for breaking or releasing the annular seal. The floating sleeve 50 will move upwardly relative to the sleeve 13 until the pin 13i engages the bottom of the slot 50d for moving the sleeve 13 and the ball 20 upwardly along with the floating sleeve 50 until the well tool T is removed from the bore O of the production tubing P at the surface G. The rotation of the inner production tubing Q moves the tubular member 11 downwardly relative to the tubular member 10 and the sleeve 13 to move the shoulder 11b into engagement with the operator shoulder 30d and move the operator 30 to the lower position for rotating the ball 20 to the open position and holding it in that position during the retrieval operation.

The foregoing disclosure and description of the invention are illustrative and explanatory thereof, and various changes in the size, shape and materials as well as in the details of the illustrated construction may be made without departing from the spirit of the invention.

I claim:

1. A well tool for controlling flow of well fluids through the bore of a first production tubing at a desired subsurface location in a well, including:

a first production tubing extending downwardly from the earth surface in a well;

a tubular housing movable through the bore of the first production tubing to and from the desired subsurface location and having a flow passage extending therethrough for enabling communication of well fluids and the like in the bore of the first well tubing past said tubular housing;

bore closure means mounted with said housing and movable to and from an open position for enabling flow of fluid through said flow passage and a closed position for substantially blocking flow of fluid through said flow passage;

a second production tubing sealingly connected with said tubular housing and having a bore disposed in flow communication with said flow passage and extending upwardly from said tubular housing within the bore of the first production tubing for forming a flow passage for well fluids from said tubular housing to the earth surface separate from the bore of the first production tubing, said second production tubing spaced from said first production tubing;

means for releasably securing said tubular housing with the first well tubing at a desired subsurface location, said means for releasably securing actuated by increasing fluid pressure in the bore of the second production tubing and said flow passage;

means for releasably sealing said tubular housing with the first production tubing to direct the flow of well fluids from the bore of the first production tubing below said tubular housing into said flow passage, said means for sealing actuated by said means for releasably securing to effect sealing when said tubular housing is secured with the first production tubing; and

actuator means mounted with said housing for effecting movement of said bore closure means to and from the open and closed positions in response to a control fluid pressure communicated to said actuator means from the bore of the first production tubing through a port in said housing located above said means for sealing and separately from the well fluids in the bore of the second production tubing wherein said well tool is operably installed in a well.

2. A well tool for controlling flow of well fluids through the bore of a well tubing, including:

a well casing extending downwardly from the earth surface in a well and secured in the well;

a first production tubing extending downwardly from the earth surface within a bore of the well casing; 15 a well packer disposed adjacent the lower end of the first production tubing for effecting a seal between the well casing and the first production tubing;

a tubular housing movable through a bore of the first production tubing to and from a subsurface location and having a flow passage extending therethrough for enabling communication of well fluids and the like in the bore of the first production tubing past said housing;

a second production tubing having a lower end sealingly secured with said tubular housing with said second production tubing movable through the bore of the first production tubing with said tubular housing, said second production tubing having a bore disposed in flow communication with said flow passage and extending upwardly from said tubular housing for forming a conduit for well fluids from said tubular housing separate from the bore of the first production tubing;

bore closure means mounted with said housing and movable to and from an open position for enabling flow of fluid through said flow passage and a closed position for substantially blocking flow of fluid through said flow passage;

means mounted with said housing for effecting movement of said bore closure means to and from the open and closed position; and

means mounted with said housing for releasably securing said housing with said first production tubing at a subsurface location in response to a controlled application of fluid pressure in said flow passage wherein said well tool is operably positioned in a well.

3. A well tool apparatus for controlling flow of well fluids through a first production tubing at a desired subsurface location in a well, including:

a tubular housing movable through a bore of the first production tubing to and from the desired subsurface location in a well and having a flow passage extending through said tubular housing for enabling communication of well fluids and the like in the bore of the first production tubing below said housing with a location above said tubular housing, said tubular housing having means for connecting and sealing said tubular housing with a second production tubing disposed within the bore of the first production tubing above said tubular housing for communicating said flow passage with the bore of the second production tubing and for supporting said tubular housing with the second production

tubing when said tubular housing moves to and from the desired subsurface location by movement of the second production tubing within the bore of the first production tubing;

seal means mounted with said housing and actuatable for blocking passage of fluids between said tubular housing and the first production tubing to direct the flow of well fluids through said flow passage of said housing;

10 bore closure means mounted with said housing and movable to and from an open position for enabling flow of fluid through said flow passage a closed position for substantially blocking flow of fluid through said flow passage;

actuator means mounted with said housing for effecting controlled movement of said bore closure means to and from the open and closed position in response to a control fluid pressure communicated to said tubular housing through the bore of the first production tubing; and

means with said housing for releasably securing said housing with the first production tubing at the desired subsurface location, said means for releasably securing actuated by the application of fluid pressure in a predetermined manner in said flow passage wherein said well tool is operably positioned in a well.

4. The well tool apparatus as set forth in claim 3, including:

said bore closure means including a ball-type valve member having a flow port formed therethrough and disposed in said flow passage for rotational movement to and from the open position with said flow port aligned with said flow passage to enable flow of fluid through said flow port and said flow passage and the closed position where said ball-type member blocks flow through said flow passage wherein rotation of said ball controls flow of fluid in the bore of the production tubing.

5. The well tool apparatus as set forth in claim 3, wherein:

said seal means when actuated expands radially outwardly for effecting an annular seal between said tubular housing and the first production tubing.

6. The well tool apparatus as set forth in claim 3, wherein said means for releasably securing includes:

a slip means mounted with said tubular housing and movable to and from a free position enabling said housing to move through the bore of the first production tubing and a locked position engaging the first production tubing for blocking movement of said housing relative to the first production tubing; and

wedge means mounted with said tubular housing and movable in response to the urging of a predetermined pressure from a first position to a second position for effecting movement of said slip means from the free position to the locked position wherein said housing is secured with the first production tubing.

7. A method of installing a controlled safety valve well tool at a desired subsurface location in a well having a first well tubing extending downwardly from the ground surface for flowing well fluids to the surface through the bore of the first well tubing, including the steps of:

connecting a safety valve well tool with a second well tubing;
 moving the safety valve to a desired subsurface location in the well through the bore of the first well tubing by moving the second well tubing into the bore of the first well tubing;
 securing the safety valve with the first well tubing at the desired location by increasing fluid pressure in the second well tubing in a controlled manner; and forming a fluid passage to the safety valve from the surface between the first well tubing and the second well tubing to communicate control fluid pressure to the safety valve from the surface wherein the safety valve well tool is installed.

8. A method of installing and operating a controlled safety valve well tool at a desired subsurface location in a well having a first well tubing extending downwardly from the ground surface for flowing well fluids to the surface through the bore of the first well tubing, including the steps of:

connecting a safety valve well tool with a second well tubing;

moving the safety valve to a desired subsurface location in the well through the bore of the first well tubing by moving the second well tubing into the bore of the first well tubing;
 securing the safety valve with the first well tubing at the desired location by increasing fluid pressure in the second well tubing;
 forming a fluid passage to the secured safety valve from the surface between the first well tubing and the second well tubing to communicate control fluid pressure to the safety valve from the surface; and
 controlling the pressure of the fluid in the fluid passage for operating the safety valve wherein the safety valve operates to control flow at the subsurface location.

9. The method as set forth in claim 8, wherein the step of controlling includes:

increasing the pressure of the fluid in the fluid passage for operating the safety valve to the open condition.
